UNITED STATES PATENT OFFICE.

SAMUEL HEINTZ, OF YOUNGSTOWN, OHIO, ASSIGNOR, BY MESNE ASSIGNMENTS, TO THE REPUBLIC RUBBER COMPANY, A CORPORATION OF OHIO.

DESIGN FOR A RESILIENT VEHICLE TIRE.

Application filed May 26, 1922. Serial No. 2,430. Term of patent 3½ years.

To all whom it may concern:

Be it known that I, SAMUEL HEINTZ, a citizen of the United States, residing at Youngstown, in the county of Mahoning and State of Ohio, have invented a new, original, and ornamental Design for Resilient Vehicle Tires, of which the following is a specification, reference being had to the accompanying drawing forming part thereof.

Figure 1 is a plan view projected to a

plane of the tread surface of the tire and showing my new design.

Figure 2 is a view of the tire in cross-section on the plane indicated by the line II—II of Figure 1.

I claim:

The ornamental design for a resilient vehicle tire, as shown.

SAMUEL HEINTZ.
